REVERSIBLE WINDOW SASH

Filed Aug. 1, 1922

2 Sheets-Sheet 2

UNITED STATES PATENT OFFICE.

DENISON MANNING, OF BIRMINGHAM, ALABAMA.

REVERSIBLE WINDOW SASH.

Application filed August 1, 1922. Serial No. 579,059.

To all whom it may concern:

Be it known that I, DENISON MANNING, a citizen of the United States of America, residing at Birmingham, in the county of Jefferson and State of Alabama, have invented certain new and useful Improvements in Reversible Window Sashes, of which the following is a specification.

My invention relates to a window sash adapted to be reversed to facilitate the cleaning of the glass on both sides from within the house.

More particularly the object of my invention is to provide a window sash which will have the same appearance as the present standard sash, which will be free to slide in the frame, and which will yet have the glass carried in an inner sash which can be lowered and reversed without disconnection from the outer sash.

A further feature of my invention consists in providing means to pivotally suspend the inner sash, when lowered, from its respective outer sash, the sashes being designed and arranged so that the pivotally suspended inner sash is free to swing about a vertical axis and to clear not only the outer sash but all the other window parts.

My invention also comprises the novel details of construction and arrangements of parts, which are hereinafter more particularly described, reference being had to the accompanying drawings which form a part of this specification, and in which:—

Fig. 1 is a vertical cross-sectional view through the center of a window frame showing the lower sash raised and its respective swinging sash in lower position from its pivot.

Fig. 2 is a perspective view of the lower sash as shown in Fig. 1, dotted lines showing the inner sash being swung on its pivot.

Fig. 3 is a partial sectional view taken on the line 3—3 of Fig. 4.

Fig. 4 is a longitudinal sectional view taken on the line 4—4 of Fig. 3.

Fig. 5 is an enlarged longitudinal sectional view of the central portion of the sash taken along the line 5—5 of Fig. 6.

Fig. 6 is a vertical sectional view taken on the line 6—6 of Fig. 5, showing the bottom rail of the pivoted sash assembled between the bottom cross rails of the outer sash.

Fig. 7 is a detail view showing the sash

pivot resting on the bottom rails of the outer sash.

Fig. 8 is a plan view of a modified form of the sash having a top cross bar carrying its pivot and used in lieu of the bottom cross bars on the outer sash.

Fig. 9 is a sectional view taken on the line 9—9 of Fig. 8.

Similar reference numerals refer to similar parts throughout the drawings.

I show my invention associated with a window frame 1 having a bottom ledge 2 and the usual vertical way strips 3 between which the upper and lower sashes are adapted to slide. My improved sash is adapted to slide up and down in the window frame just as is at present customary, and each of the sashes is provided with the usual sash cords 4 connected to sash weights by which it is suspended. I have illustrated my invention in detail more particularly as applied to the lower sash but the principles of construction are the same for the upper sash.

Referring now to Fig. 2, which shows the lower sash in detail, the same comprises an outer sash having sides 5, a top 6 and a pair of spaced bottom rails 7 connecting the sides and disposed at the front and rear of the vertical grooves 8 provided in the inner faces of the sides. These grooves 8, as shown more clearly in Figs. 3 and 4, form slideways which are adapted to receive the inner sash comprising a top rail 9, side rails 10, and a bottom rail 11, either connected to or formed integral with a bottom bar 12, which extends on each side beyond the sides 10 and is adapted, when raised, to be received in and to close the space formed between the bottom shoulders 13 on the outer sash sides 5 which, it will be noted, are offset from the grooves 8. The bottom rail 11 is adapted to fit snugly between the bottom rails 7 of the outer sash, as is shown more clearly in Fig. 6. In the inner sash I mount the glass 14 in the manner well understood in the art and at the center of the top rail 9 I attach a bracket 15 carrying a vertical pivot stud 16 having an enlarged bevelled head 17 thereon. This head is adapted to be received in an enlarged circular socket formed in the under side of the upper rail 6 of the outer sash, which rail also has a transverse groove or channel 19 which receives the upper rail 9 of the inner sash to

give a weather tight joint. This upper rail 6 carries a bevelled latch pin 20 having a grip 21 exposed on the inner side of the sash and engaged by a flat spring 22, also attached to the rail 6 and normally pressing the latch into the opening 18 where it is adapted to engage under the button head 17 and support the lower sash in raised position, as shown in the upper sash in Fig. 1. 5 The button head is larger than the space between the bottom rails 7 of the outer sash but is small enough to pass up through the notches 23 provided at one side in said rails 7, (see Fig. 2). The length of the shank 16 10 is greater than the depth of the rails 7, as seen in Fig. 7, and thus when the inner sash is lowered, after releasing the latch 20, its button will engage the rails 7 and thus pivotally support the lower sash with its upper 15 rail 9 slightly below the level of the rails 7 and clear of the grooves 8 and spaced from the shoulders 13. It will be observed, by reference to Fig. 4, that the inner wall of each slideway 8 is sufficiently spaced from 20 the inner wall of the adjacent shoulder 13 to leave an ample clearance for the side rails 10 of the inner sash, in swinging about its vertical center, to clear these shoulders 13. 25 In Figs. 8 and 9 I have shown a modification in which the bottom rails 7 of the outer sash are omitted and I provide along the inner wall of each slideway groove 8 a groove 24 which stops just short of the lower end of the slideway, thereby leaving a stop 30 shoulder 25. To the center of the top rail 9 of the inner sash I pivot by means of a pin 26 a cross bar 27 having its ends 28 reduced and adapted to overhang the side edges of the inner sash and to travel in the grooves 35 24. It follows that this bar 27 will be arrested by the shoulders 25 when the inner sash has been fully lowered and will pivotally support the latter with its top rail 9 clear to swing about its vertical axis and 40 thus present both sides of the glass to be cleaned. The cross bar 27 is undercut below its ends 28 and is designed so that by cocking the lower sash this bar can be disengaged from the slideway grooves 8 and the 45 inner sash entirely removed if desired. Any suitable latch means may be provided to hold the inner sash in raised position.

In operation, referring to Figs. 1 to 7, the outer sash is mounted to slide in the sash frame guides in the customary manner. The inner sash, disposed at an angle to the outer sash, is shifted into position so that its pivot pin 17 can be inserted upwardly through the notched portions 23 of the outer sash rails 7 and then shifted to central position, after which by turning the inner sash parallel with the outer sash, the inner sash can be run up into the slideway grooves 8 and its pivot pin head 17 engaged by the latch 20 which will thus hold the sashes assembled

in operating position. In this position, the assembled sash presents no appreciable difference in appearance from the ordinary sash and all joints are of such character as to prevent any appreciable air leakage. 70

In cleaning the window the inner side of the glass is first cleaned as usual, then the sash is lowered, the latch is released and the weights lift the outer sash to its uppermost position in which its rails 7 catch the pivot 75 pin 17 so as, on further raising of the outer sash, to suspend the lowered inner sash in position to be reversed when, if desired, it can be run up in the outer sash and latched, before being cleaned. By repeating the operation, the inner sash can be again reversed to its normal position. 80

The operation as thus described is substantially the same for the modification shown in Figs. 8 and 9. It is to be understood that my double sash can be made up of wood or metal, or wood and metal and that any suitable arrangement of both latch and pivot can be substituted. 85

Though I have described with great particularity the details of the embodiment of the invention herein shown, it is not to be construed that I am limited thereto as changes in arrangement and substitution of equivalents may be made by those skilled in the art without departing from the invention as defined in the appended claims. 90

Having thus described my invention, what I claim as new and desire to secure by Letters Patent, is:— 100

1. A window sash, comprising an outer sash having side grooves, an inner sash slideable from the bottom up into said grooves which open through the bottom of the outer sash, releasable means to hold the sashes in assembled position, and means to pivotally support the inner sash from the outer sash clear of the latter's side grooves. 105

2. A window sash as in claim 1, in which said pivotal support means comprises a stop at the bottom of the outer sash, and a pivot member connected to the top of the inner sash and adapted to engage said stop. 110

3. A window sash as in claim 1, in which said pivotal support means comprises a pivot at the center of the top of the inner sash, and means to connect and support the pivot from the outer frame with the inner sash hanging clear of said outer sash. 115

4. A window sash, comprising an outer sash having side grooves and bottom shoulders outwardly offset from the adjacent grooves, an inner sash slideable in said grooves, means to hold the sashes interlocked, and means to pivotally support the inner sash from the outer sash clear of said side grooves and free to swing between said shoulders about a vertical central axis. 120

5. In combination, an outer sash adapted to slide vertically between way strips in a 125

frame, there being grooves in the inner sides of the sash which normally stop short of lapping the way strips, an inner sash vertically slidable into the outer frame through 5 its bottom, means to hold the sashes interlocked, and means to suspend the inner sash on a central vertical pivot from the raised outer sash in position to clear said sash and frame for rotation about said pivot.

10 6. A window sash comprising an outer sash adapted to be slidably mounted in the

window frame, an inner sash slidable in the outer sash, means to pivotally connect said sashes with the inner sash lowered to clear the upper sash and frame, and releasable 15 means to hold the sashes telescoped in operative relation.

In testimony whereof I affix my signature.

DENISON MANNING.
